TYPE-WRITING MACHINE.

1,147,300.

Specification of Letters Patent.

Patented July 20, 1915.

Application filed October 17, 1913. Serial No. 795,667.

To all whom it may concern:

Be it known that I, ARTHUR J. BRIGGS, citizen of the United States, and resident of Syracuse, in the county of Onondaga and 5 State of New York, have invented certain new and useful Improvements in Type-Writing Machines, of which the following is a specification.

My invention relates to typewriting machines and more particularly to escapement mechanism for such machines.

The main object of my invention, generally stated, is to provide escapement mechanism which is simple in construction, efficient in use and which may be manufactured at small cost.

To the above and other ends which will hereinafter appear, my invention consists in the features of construction, arrangements 20 of parts and combinations of devices set forth in the following description and particularly pointed out in the appended claims.

In the accompanying drawings wherein like reference characters indicate corresponding parts in the various views, Figure 1 is an enlarged fragmentary side elevation with parts in section of one form of typewriting machine embodying my invention, only so much of the machine being shown as 25 may be necessary to illustrate my invention in its embodiment therein. Fig. 2 is an enlarged detail fragmentary rear elevation showing a portion of the escapement mechanism, the parts being shown as they are disposed at the end of the depression of a finger key. Fig. 3 is a like view of the same with parts broken away and showing the escapement members as they appear when the carriage is being returned to the right. Fig.

40 4 is a view corresponding to Fig. 3 but showing the parts as they appear when the holding dog is maintained in its lowermost position to release the carriage. Fig. 5 is an enlarged fragmentary rear elevation showing 45 the carriage, the escapement mechanism and some of the associated parts. Fig. 6 is an enlarged detail top plan view of the dog rocker. Fig. 7 is a central fore and aft sectional view of the machine with parts broken 50 away and parts omitted. Fig. 8 is a detail fragmentary front elevation of the space key and some of the associated parts.

I have shown my invention in the present instance embodied in a front-strike type-writing machine of the character disclosed

in my previously filed applications, Serial Nos. 782,859, 786,107, 786,108, 790,583 and 791,734, although it should be understood that the invention may be embodied in other styles of typewriting machines.

The frame of the machine comprises side plates 1 united by a front cross plate 2, a type bar segment 3 and a keyboard plate 4. Segmentally arranged upwardly and rearwardly swinging type bars 5 are adapted to 60 strike against the front face of the platen 6. Each type bar is pivoted at 7 on a type bar hanger 8 secured to the front face of the segment 3 by screws 9. Each type bar has a pull link 10 connected thereto, the forward end of said link being pivoted at 11 to an actuating lever 12 pivoted at 13 to a fixed portion of the machine. A key stem 14 carrying a finger key 15 is pivoted at its lower end, as at 16, to the associated actuating 70 lever 12. The key stems 14 extend through guide openings in the keyboard plate and are guided at their upper end portions thereby.

The platen 6 is mounted on a platen shaft 80 17 which is received in bearing openings in end plates 18 of the carriage. These plates are fixed to and extend upwardly from a traverse bar 19 which with the end plates 18 and a tie rod 20 constitute the carriage 85 or platen carrier. The traverse bar 19 is oppositely grooved to form race-ways 21 and 22 for the reception of anti-friction balls or rollers 23, 24, respectively. A shift bar, rail or frame, designated as a whole by the 90 reference numeral 25, is grooved in its forward face at 26 to form a race-way to receive the anti-friction balls 24. A plate 27 is secured by screws 28 to the shift rail, and is grooved at 29 to form a race-way to receive 95 the bearing balls 23. The carriage or platen carrier is thus supported on the shift rail for case shifting movement therewith and for movement on the shift rail from side to side of the machine. The carriage is propelled in the direction of its feed by a spring 30 drum 30 to which one end of a band 31 is connected; the other end of said band being connected with a carriage intermediate the two sets of bearing rollers 23, 24. The 100 power of the spring drum is thus exerted on the carriage to propel it in the direction of its feed, or from right to left, under control of the escapement mechanism to be herein-after described. The carriage and the 110

means for mounting the same are claimed in my application, Sr. No. 782,859, hereinbefore referred to.

Substantially horizontally disposed parallel links 32 are connected to the shift rail 5 and to the frame of the machine to guide the shift rail and the parts carried thereby in their case shift movements. Thus, the forward end of each link 32 is pivoted at 33 to the shift rail, whereas the rear end of each of said links is pivoted at 34 to the frame of the machine. The shift rail carries depending arms 35 to the lower ends of which are pivoted, at 36, a second set of parallel links 37. These links are pivoted at 38 to the frame of the machine and are extended rearwardly beyond their pivots 38 to form arms or links 39 which are fixedly connected with a tie-rod or cross bar 40. The shift rail and the parts carried thereby are thus supported for case shifting movement under control of suitable case shift mechanism such, for example, as that disclosed in my application, Sr. No. 791,734, hereinbefore referred to.

The escapement mechanism in the present instance comprises a feed rack 41 and feed dogs, designated as a whole by the reference numerals 42 and 43, respectively. The feed rack is fixed to the carriage or platen carrier by screws 44, whereas the feed dogs 42 and 43 are pivoted at 45 and 46, respectively, on opposite sides of a dog rocker 47, which latter is carried by and shiftable with the shift rail during the case shifting movements of the latter, as will hereinafter more clearly appear. It will be seen that the engaging tooth of the feed dog 42 extends upwardly from its lever-like carrier 48 of which it forms a part, said carrier being in the nature of a lever of the first order. This lever-like carrier is mounted on one side of the plate-like dog rocker 47 and the engaging tooth or dog 45 thereon normally engages a tooth of the feed rack, as indicated in Fig. 1, and constitutes a holding dog. The carrier 48 of this dog is received in a cut-out portion 49 (see Fig. 6) in one side of the dog rocker, and a contact portion 50 on the member 48 is adapted to overlap and engage a contact portion 51 on the dog rocker, in order to limit the turning movement of the dog carrier 48 in one direction around its pivot 45. The dog 55 carrier 48 carries a rearwardly extending pin 52 for purposes which will hereinafter appear. One end of a contractile spring 53 is connected to a rearwardly extending pin 54 on the dog carrier 48, the opposite end of 60 this spring being connected to a pin 55 which extends rearwardly from the carrier 56 of the dog 43. The power of this spring therefore is exerted on both dogs and tends to return them to normal position. From an inspection of Figs. 2 and 6 it will be ob-

served that the dog rocker is formed with two shoulders 57 and 58 between which the carrier 56 of the feed dog 43 is received, these shoulders or abutments limiting the movement of the carrier 56 to and from 70 normal position. It will be understood that the feed dog 43 constitutes a stepping dog which has a movement around its pivot 46 in the general direction of the length of the feed rack 41. It will also be seen that 75 the feed dog 42 is fixed against movement in the direction of the length of the feed rack, thus constituting a holding dog, but that said dog has a movement around its pivot 45 substantially at right angles to the 80 length of the feed rack in order to move into and out of engagement with the teeth of the latter. The force of the spring 53 is exerted to normally maintain the carrier of the feed dog 43 against the abutment 57, as 85 indicated in Fig. 5, and also to normally maintain the feed dog 43 up in engagement with the feed rack, as shown in said figure.

The dog rocker 47 is provided with trunnion-like pivots 59 and 60, the pivot 59 being received in a bearing opening in an ear 61 of a bracket 62 which is secured by screws 63 to the shift rail 25. From an inspection of Fig. 5 it will be seen that the trunnion-like pivot 60 of the dog rocker is received in the recessed end of a screw 64, which latter is threaded into a tapped opening in an ear 65, corresponding to the ear 61 and like it projecting from the bracket 62. A lock nut 66 is threaded onto the screw 64 to hold it against accidental displacement from the position to which it is adjusted. The dog rocker has a depending projection or arm 67 to which one end of a contractile spring 68 is connected, the opposite end of said spring being connected to a depending arm 69 on the bracket 62. The power of this spring is exerted to normally maintain the dog rocker in the position shown in Fig. 1, with the holding dog 42 in engagement with the feed rack. From the foregoing description it will be understood that the dog rocker is carried by the shift rail and shifts with the latter during its case shifting movements.

Motion is transmitted to the dog rocker at each printing operation in the following manner: A universal bar 70, which is segmental in form, is arranged above the type bars in the rear of the pivots thereof. This universal bar is bent at its forward edge, as indicated at 71, to form a contact face with which the forward edges of the type bars, near the heels thereof, contact during the movements of the type bars to the printing position. The universal bar has rearwardly extending lugs 72 to which are riveted, at 73, bracket-like supporting members 74 which are pivoted, at 75, to upwardly extending parallel supporting arms 76 and 77. The

lower ends of these supporting arms are provided with sleeves 78 fixed by pins 79 to a rock shaft 80. One end of the rock shaft is reduced to form a pivot 81 which is seated in a bearing opening in the ear 82 of a bracket 83, the latter being secured by screws 84 to the type bar segment 3. The opposite end of the shaft 80 is reduced to form a pivot 85 which is seated in a recessed end of a screw 86 threaded into a tapped opening in an ear 87 on the bracket 83. A lock nut 88 is threaded onto the screw 86 in order to hold it against accidental displacement from the position to which it is adjusted.

Connected with the universal bar about midway in the length thereof is a rearwardly directed plate-like arm 89 provided with a foot-piece 90 by which the arm may be riveted, at 91, to the universal bar. This arm is enlarged to form a vertically disposed plate-like actuating member 92. A centrally disposed upright supporting link 93 is pivoted at its upper end, as at 94, to the actuating member and is pivoted at its lower end, as at 95, to an ear 96 on the bracket 83. This link 93 with the parallel supporting arms 76 and 77 constitute means for supporting the universal bar and the actuating plate 92, fixedly connected therewith, on the frame of the machine and for movement fore and aft of the machine. The rear edge of the plate-like actuating member constitutes contact faces 97—98 which are adapted to coöperate with the dog rocker to actuate it. Thus a depending arm 99 on the dog rocker is provided with an offset engaging member 100 which extends into the path of the actuating member 92, as indicated in Figs. 1 and 5. During a rearward movement of the universal bar the actuating member 92 will be brought into contact with the engaging portion 100 of the dog rocker in order to turn said dog rocker on its pivots, irrespective of the position to which the dog rocker may be shifted with the shift rail. It will be seen that the contact face 98 on the actuating member extends rearwardly further than the contact face 97. This is in order that the actuating member may properly coöperate with the dog rocker when the platen is shifted to its uppermost position, it being understood that the platen and the dog rocker which moves therewith receive an upward and rearward movement from the lowest to the uppermost position.

In order to limit the return movement of the dog rocker around its pivot, I have provided a set screw or adjustable stop 101 which is received in a tapped opening in the depending arm 99 and extends through said opening and is adapted to contact at its forward end with an angular stop 102 (see Figs. 1 and 5). The stop 102 projects from an ear 103 carried by a depending arm or plate-like portion 104 of the bracket 62

which, as hereinbefore explained, is carried by the shift rail of the machine.

I have provided means whereby the actuating member 92 is effective not only to actuate the escapement mechanism, but is also effective to actuate the ribbon feed mechanism and ribbon vibrator as is more clearly brought out in my applications, Sr. Nos. 802,785 and 805,927, filed respectively, November 24th, and December 11th, 1913, in which cases two specifically different forms of ribbon mechanism are claimed. I have shown in the accompanying drawings an actuating lever 105 by which motion is transmitted from the actuating member 92 to the ribbon feed mechanism and vibrator (not shown). This actuating lever 105 is provided with a trunnion-like pivot 106 which is fixed thereto and is reduced at one end to form a pivot 107. The pivot 107 is received in the recessed end of a bearing screw 108 threaded into a tapped opening in an ear 109, which corresponds to the ear 103 and like it projects from the bracket plate 104. The opposite end of the trunnion-like portion 106 is reduced at 110 to form a pivot which is received in a bearing opening in the ear 103. A contractile spring 111 is connected at its lower end to a bracket arm 112, secured by a screw 113 to the bracket plate 104. The opposite end of the spring is connected to a pin 114 which projects from the trunnion 106. The power of this spring is exerted to return the lever 105 and the parts connected therewith, including the actuating member 92 and the universal bar 70, to normal position. Operative connection between this lever and the actuating member 92 is effected by a pin 115 which projects laterally from the lever 105 and extends into a curved slot 116 provided in a depending arm 117 on the actuating plate 92. This slot extends upwardly in the plate, corresponding in contour to the path of movement of the pin 115 in the movement of the latter during the case shifting movements of the platen. It will be understood that the lever 105 is thus operatively connected with the universal bar to be actuated by the latter at each printing operation, the movement of the universal bar effecting a pivotal movement of the lever to actuate the ribbon vibrator and ribbon feed mechanism (not shown) controlled thereby. It will also be understood that the lever 105 partakes of the shifting movement of the platen in the case shifting movements of the latter and at such time moves independently of the actuating member 92.

In order to effect a release of the carriage from control of the escapement mechanism, I have provided a releasing bar 118 which extends throughout, or substantially throughout, the length of the carriage and is fixed at its ends in supporting arms 119, 120. The arm 119 is pivoted on a headed 130

pivot screw 121 received at its threaded end in a tapped opening in the right-hand end plate 18 of the carriage, a washer 122 being interposed between the arm and said end plate. The arm 120 is pivotally supported in a like manner to the right-hand end plate 18 of the carriage. Thus a headed pivot screw 123 is received at its threaded end in the left-hand end plate 18 of the carriage and a spacing sleeve 124 is interposed between the arm 20 and said end plate. The arm 120 is extended forwardly and upwardly where it is provided with a finger piece 125 by which the releasing rod or bail 118 may be controlled. A contractile spring 126 is connected at one end to a pin 127 which projects from the arm 120, the opposite end of said spring being connected to a pin 128 which projects from the left-hand end plate 18 of the carriage. The power of this spring is exerted to return the releasing bar to normal position. From an inspection of Fig. 1 it will be understood that the releasing bar 118 is arranged above the pin 52 on the dog carrier 48. A depression of the finger piece 125 is effective therefore to move the bar 118 downwardly against the pin 52, thereby turning the carrier 48 on its pivot 45 to the position represented in Fig. 4. This movement disengages the holding dog 42 from the feed rack in order to free the carriage from the control of its escapement mechanism and enable the carriage to be moved in either direction.

35 I have provided independent means for controlling the escapement mechanism from the space key of the machine. Thus from an inspection of Figs. 7 and 8 it will be seen that a space key or bar 129 has a sheet metal bracket 130 secured thereto by screws 131. This bracket has depending ears or lugs 132 to which a yoke-like member, designated as a whole by the reference numeral 133, is secured by screws 134. This yoke-like member 133 is provided with widely separated arms 135 by which it is attached to the ears 132 and a centrally disposed depending arm 136 projects from the cross bar of the yoke-like member. Each arm 135 has an ear 137 formed thereon to which a broad substantially horizontally disposed link 138 is pivoted at 139. The width of this link corresponds substantially to the width of the yoke-like member 133 at the broadest portion of the latter. The rear end of the link 138 is pivoted at 140 in upright ears 141 of a bracket 142, the latter being secured to a supporting plate 143 fixed to the frame of the machine. The lower end of the arm 136 is slotted at 144 to receive the shank of a headed screw 145. The threaded end of the screw is received in a tapped opening in a crank arm 146 which extends from a hub 147, the latter being fixed on a rock shaft 148 near the forward end thereof. This

rock shaft extends fore and aft of the machine and is received at its forward end in a bearing opening in the cross plate 2 of the frame, the rear end portion of the rock shaft extending through a bearing opening 70 in the type bar segment 3. A collar 149 is secured to the rock shaft to prevent longitudinal movement of the latter in one direction, said collar bearing against the type bar segment. Longitudinal movement of 75 the rock shaft in the opposite direction is prevented by the hub 147 bearing against the cross plate 2. A contractile spring 146 is connected at one end to the crank arm 146 and at its opposite end to a pin 146 which projects forwardly from the cross plate 2 of the machine. This spring is effective to restore the crank arm 146 and the parts connected therewith to normal position. The rear end of the rock shaft 85 148 has a crank arm 150 secured thereto. This crank arm, as will be best understood from an inspection of Figs. 1 and 5, overlies a crank arm 151 which projects from the hub 78 of the supporting arm 76. It 90 will be understood, therefore, that a depression of the space key 129 is effective to turn the rock shaft 148 and to communicate movement through the crank arms 150 and 151 to the universal bar and the parts controlled thereby to effect a letter feed movement of the carriage.

In the operation of the machine a depression of the finger key 15 is effective to actuate the universal bar and transmit movement to the actuating member 92. This in turn operates on the dog rocker to effect a pivotal movement of the latter. A depression of the finger key is effective, therefore, to move the holding dog out of engagement 105 with the tooth of the feed rack and to bring the aligned stepping dog into engagement with the same tooth. The power of the carriage spring exerted through the feed rack on the engaged stepping dog will overcome 110 the power of the spring 53, thus moving the stepping dog to the position shown in Fig. 2 and affording a letter space movement of the carriage. When pressure on the finger key is released the universal bar will be 115 returned to normal position by the spring 111, and the dog rocker will be returned to normal position by its spring 68. This return movement of the dog rocker disengages the stepping dog from the engaged tooth of the 120 feed rack and the stepping dog is returned to normal position around its pivot 46 by the spring 53. The same movement is effective to again bring the holding dog 42 into engagement with a tooth of the feed 125 rack.

It will be seen that each type bar is not brought into cooperation with the universal bar until after the former has been set in motion and has completed about one-half 135

of its travel to the printing position, and that the actuating member 92 moves throughout, say, three-fifths of its travel with the universal bar before it takes up 5 and moves the dog rocker. It will be understood, therefore, that the escapement mechanism is not actuated until just before the type bar reaches the printing position when the "let-off" of the carriage occurs, 10 thus providing a rapid "reverse" feed and providing a light "touch" by reason of the fact that each type action is set in motion before any resistance is offered by the universal bar or by the escapement mechanism 15 which it controls, and that these parts are taken up successively and not until late in the printing movement of the type bar. Moreover, while most of the parts are made of sheet metal and are comparatively light 20 and inexpensive to manufacture, they are durable and efficient in action and are not liable to become deranged or broken.

While I have shown with considerable detail one form of mechanism embodying my 25 invention, it should be understood that various changes may be made without departing from the spirit and scope of the invention and that some parts may be employed without others.

30 What I claim as new and desire to secure by Letters Patent, is:—

1. In a typewriting machine, the combination of a carriage; a series of type bars; a segmental universal bar actuated thereby; 35 escapement mechanism controlled by said universal bar; a space key; a rock shaft which extends fore and aft of the machine and which is controlled by said space key; and intermediate operative connections between 40 said rock shaft and said universal bar, said intermediate operative connections comprising a supporting arm on which the universal bar is mounted, a crank arm on said supporting arm, and a co-operating 45 crank arm on the rock shaft.

2. In a typewriting machine, the combination of a carriage, a series of type bars, a segmental universal bar actuated thereby, escapement mechanism controlled by said 50 universal bar, a space key, a depending arm on said space key, a rock shaft which extends fore and aft of the machine, a crank arm on said rock shaft with which said depending arm on the space key is connected, 55 and operative connections between said rock shaft and the universal bar.

3. In a typewriting machine, the combination of a carriage, a series of type bars, a segmental universal bar actuated thereby, 60 escapement mechanism controlled by said universal bar, a space key, a depending arm on said space key, a rock shaft which extends fore and aft of the machine, a crank arm on said rock shaft with which said depending arm on the space key is connected,

a second crank arm on said rock shaft, a supporting arm for the universal bar, and a crank arm on said supporting arm and with which said second crank arm on the rock shaft co-acts.

4. In a typewriting machine, the combination of a space key, a yoke-like depending member secured thereto, a guide link extending fore and aft of the machine and pivoted at its rear end to a fixed part of the 75 machine and at its forward end to said yoke-like member, escapement mechanism, and intermediate operative connections between said yoke-like member and said escapement mechanism.

5. In a typewriting machine, the combination of a space key, a yoke-like depending member secured thereto, a broad guide link extending fore and aft of the machine and pivoted at its rear end to a fixed part of the machine and at its forward end to the two 85 arms of said yoke-like member, escapement mechanism, and intermediate operative connections between said yoke-like member and said escapement mechanism, said operative 90 connections including a rock shaft which extends fore and aft of the machine and which is operated by said yoke-like member.

6. In a typewriting machine, the combination of a space key, a yoke-like depending member secured thereto, a broad guide link extending fore and aft of the machine and pivoted at its rear end to a fixed part of the machine and at its forward end to the two 100 arms of said yoke-like member, the width of said link being substantially co-extensive with the width of the yoke-like member at the broadest portion thereof, a crank arm to which the lower end of the yoke-like member is connected, escapement mechanism, 105 and intermediate operative connections between said crank arm and said escapement mechanism.

7. In a typewriting machine, the combination of a carriage; and escapement mechanism therefor comprising a feed rack, a dog rocker, a stepping dog pivoted on one side of the dog rocker to move in the general direction of the length of the feed rack, and a holding dog pivoted on the other side 115 of the dog rocker for movement thereon at substantially right angles to the length of the feed rack and into and out of engagement therewith.

8. In a typewriting machine, the combination of a carriage; and escapement mechanism therefor comprising a feed rack, a dog rocker, a stepping dog pivoted to the dog rocker to move in the general direction of the length of the feed rack, a holding dog pivoted on the dog rocker for movement thereon at substantially right angles to the length of the feed rack and into and out of engagement therewith, and a single contractile spring operatively 120 connected to the carriage and the dog rocker.

- 6
 nected at one end to the holding dog and at its opposite end to the stepping dog and operative on both dogs.
9. In a typewriting machine, the combination of a carriage; and escapement mechanism therefor comprising a feed rack, a dog rocker, a stepping dog pivoted on one side of the dog rocker to move in the general direction of the length of the feed rack; 10 a holding dog pivoted on the other side of the dog rocker for movement thereon at substantially right angles to the length of the feed rack and into and out of engagement therewith, and a release bar carried by and 15 movable on the carriage and extending substantially throughout the length thereof and operative on said holding dog to move it out of engagement with the feed rack.
10. In a typewriting machine, the combination of a carriage, a series of type bars, 20 a segmental universal bar actuated by said type bars, an actuating member in the nature of a vertically disposed plate which is connected to the universal bar about midway 25 in the length thereof and the rear edge of which plate constitutes a contact edge, and escapement mechanism including a dog rocker which is actuated by the rear contact edge of said actuating member.
30. 11. In a typewriting machine, the combination of a platen, a shiftable platen carrier, a series of type bars, a segmental universal bar actuated by said type bars, an actuating member which is fixedly connected 35 to the universal bar, and escapement mechanism including a dog rocker which is acted upon directly by said actuating member and which is shiftable relatively thereto when the platen receives a case shifting movement.
40. 12. In a typewriting machine, the combination of a platen, a shiftable platen carrier, a series of type bars, a segmental universal bar actuated by said type bars, an actuating member in the nature of a vertically disposed plate which is connected to the universal bar and the rear edge of which plate constitutes a contact edge, different portions of which extend rearwardly different distances, and escapement mechanism including a dog rocker which is actuated by the rear contact edge of said actuating member and which is shiftable relatively thereto when the platen receives a case shifting movement.
55. 13. In a typewriting machine, the combination of a carriage; a series of type bars, a segmental universal bar actuated by said type bars; an actuating member in the nature of a vertically disposed plate which is 60 connected to the universal bar about midway in the length thereof and the rear edge of which plate constitutes a contact edge; escapement mechanism including a dog rocker which is actuated by the rear contact edge of said actuating member; and a lever connected to said actuating member.
14. In a typewriting machine, the combination of a platen; shiftable platen carrier; a series of type bars; a segmental universal bar actuated by said type bars; an actuating member which is connected to the universal bar; escapement mechanism including a dog rocker which is actuated by said actuating member and which is shiftable relatively thereto when the platen receives a case shifting movement; and a lever operatively connected to said actuating member to be moved thereby under the movement of the universal bar but to afford a movement of said lever independently of the actuating member when the platen receives a case shifting movement.
15. In a typewriting machine, the combination of a carriage, an escapement mechanism therefor comprising a feed rack, a dog rocker, an upright dog carrier pivotally mounted upon said rocker, and, with its dog, having a movement in the general direction of the length of said rack, and a second dog carrier substantially horizontally arranged and separately pivotally mounted on said rocker and, with its dog, having a movement substantially at right angles to the length of said rack, the pivot of the said second dog carrier being intermediate the ends thereof, a stop arranged to co-act with the outer end of said second dog carrier, and a spring for normally holding the outer end of said second dog carrier against said stop, the inner end of said second dog carrier being depressible to move the dog thereon down out of engagement with the rack.
16. In a typewriting machine, the combination of a carriage, an escapement mechanism therefor comprising a straight feed rack, a dog rocker thereunder, an upright dog carrier pivoted on said rocker, another substantially horizontal dog carrier also pivoted on said rocker, and a spring connected to and extending between said dog carriers.
17. In a typewriting machine, the combination of a carriage, an escapement mechanism therefor comprising a straight feed rack, a dog rocker, a stepping dog movable between stops lengthwise of said rack and mounted on an upright carrier pivoted to said rocker, a holding dog movable transversely of said rack and mounted on a carrier that is arranged transversely of the stepping dog carrier and that is also pivoted to said rocker and normally bears against a stop thereon, and a coiled spring connecting both said dog carriers.
18. In a typewriting machine, the combination of a carriage, an escapement mechanism therefor comprising a straight feed rack, a dog rocker thereunder two dog carriers independently pivotally mounted on

said rocker, one in a substantially upright position and the other in a substantially horizontal position, said dog carriers being pivoted between their ends and the upright carrier being provided with a stepping dog and the substantially horizontal carrier being provided with a holding dog, and a coiled spring joining the outer ends of both of said dog carriers.

19. In a typewriting machine, the combination of a carriage, an escapement mechanism therefor comprising a plate-like dog rocker pivotally mounted at its side edges and having the cut-out 49 and the stops 51, 57 and 58, an upright dog carrier pivotally mounted on one side of said dog rocker, and a substantially horizontal dog carrier also pivotally mounted on the other side of said rocker, and the first mentioned dog carrier being adapted to the stops 57, 58, and the last being adapted to the stop 51.

20. In a typewriting machine, the combination of a carriage, an escapement mechanism therefor comprising a plate-like dog rocker having pivotal portions at its sides, a stepping dog and a holding dog separately pivotally mounted on said rocker, an arm depending from said plate-like portion below the pivotal axis of the rocker, a universal bar, and an actuator connected thereto and adapted to be moved into and out of contact with said arm to operate said dog rocker.

21. In a typewriting machine, the combination of a shifting carriage, a feed rack, and a dog rocker adapted to shift with said carriage, said dog rocker being pivotally mounted at its sides and carrying stepping and holding dogs and having also an arm depending below the pivotal axis of the rocker, a universal bar, and an actuating device for said dog-rocker arm having a plurality of points of contact for the normal and shifted positions of said arm.

22. In a typewriting machine, the combination of a shifting carriage, a feed rack and a dog rocker adapted to shift therewith, the dog rocker being pivoted and carrying stepping and holding dogs and having also a depending arm, a non-shifting plate-like actuator having stepped contact portions for said arm, and a universal bar adapted to operate said actuator.

23. In a typewriting machine, the combination of key actuated type bars, a universal bar adapted to be actuated by said type bars, a plate-like vertically arranged actuator connected to said universal bar and having a plurality of contact portions at its rear edge, a pivoted dog rocker having a depending arm adapted for contact by said actuator, stepping and holding dogs mounted on said dog rocker, a feed rack, and a carriage; said dog rocker, feed rack and carriage all being shiftable.

24. In a typewriting machine, the combination of a carriage, a feed rack, a dog rocker, all of said parts being shiftable, the dog rocker carrying stepping and holding dogs and being horizontally pivoted, a part extending below the pivots of the dog rocker, and a reciprocatory actuator connected to the universal bar and adapted when the type bars are operated to strike said downward extension from the dog rocker, a return spring for said dog rocker, and stops for arresting the return movement of the latter, one of said stops being arranged on said downward extension and the other on a part that shifts with the carriage.

Signed at Syracuse, in the county of Onondaga, and State of New York, October, A. D. 1913.

ARTHUR J. BRIGGS.
